UNITED STATES PATENT OFFICE.

JOHN T. L. BROWN, OF NEW BRIGHTON, NEW YORK, ASSIGNOR TO WESTERN ELECTRIC COMPANY, INCORPORATED, OF NEW YORK, N. Y., A CORPORATION OF NEW YORK.

OSCILLATION GENERATOR.

Application filed December 3, 1923. Serial No. 678,117.

This invention relates to a method of and means for producing oscillations, and more particularly to the production of oscillations of variable frequency and amplitude.

5 It has heretofore been proposed to generate oscillations of variable frequency and amplitude by continuously rotating a capacity or inductance element included in the frequency determining circuit of an oscillator, comprising an electric discharge device having associated input and output circuits coupled in feed-back relation.

In a paper published in the journal of A. I. E. E. for May 1920, R. A. Heising 15 points out at page 476 et seq., that the behavior of an oscillator comprising a three electrode electric discharge device having coupled input and output circuits is dependent, among other things, upon the space current, grid current, and oscillating current 20 flowing in the circuits associated with the discharge device.

The present invention provides a self-oscillating system including a three electrode 25 electric discharge device, in which the impedance of the device is cyclically controlled to recurrently produce a succession of electric waves, the frequency and amplitude of which simultaneously vary over a definite 30 range.

In accordance with this invention an electric discharge device, including a cathode, an anode and a control electrode or grid having its associated input and output circuits 35 intercoupled to constitute an oscillating system, has a condenser of relatively large capacity, inserted in series with its control electrode, which is gradually charged by current flowing in the grid circuit to render 40 the system non-oscillatory and a relay in its output circuit to discharge the condenser to restore the system to an oscillatory condition; whereby the system may be controlled to continuously produce a succession of 45 damped oscillations of desired variable frequency and amplitude.

The foregoing briefly describes one practical embodiment of the invention, but it is not intended to define the scope of the present invention. The novel features and combinations which are believed to be character-

istic of this invention will be pointed out with particularity in the subjoined claims.

One object of the invention is to provide an oscillator adapted to produce a damped 55 oscillation.

Another object is the provision of an arrangement for recurrently producing a train of oscillations, each of which is of variable frequency and amplitude.

Another object of the invention is to simplify and improve the operation of oscillation generators for producing oscillations simulating, as to frequencies and energy content, the sound waves of human speech. 60

For a complete understanding of the invention reference may be made to the following specification read with reference to the attached drawing, in which:—

Fig. 1 illustrates the invention as used to supply current of variable frequency and 70 amplitude for agitating the granular particles of a microphone, and

Fig. 2 shows an oscillogram of the oscillating current produced in the anode-cathode circuit of the oscillator. 75

Referring to Fig. 1, there is shown an electric discharge device comprising a vessel 1 enclosing a cathode 2, an anode 3 and a grid or control electrode 4.

Heating current is supplied to the cathode 80 4, and to the cathode of a second discharge device 18 by the source 5.

The input circuit of the discharge device may be traced from the cathode 2 through the tuned circuit, comprising an inductance 85 7 connected in parallel with a condenser 8, and condenser 9 to the grid 4. In shunt to the condenser 9 is a circuit including a resistance 10 and contacts 11.

The output circuit may be traced from the 90 cathode 2, plate source 12, herein shown as a battery, an inductance 13, coil 14, relay 15, anode 4 and across the space within the device to the cathode 2. A condenser 16 connected in shunt to the relay 15 serves as 95 a low impedance path for the oscillating current. Coil 14 is the primary winding of a repeating coil, the purpose of which will be described hereinafter.

The coil 13 is inductively associated with 100 the coil 7 included in the tuned circuit to

supply increments of energy to the input circuit of the device 1 to control the production of oscillations.

The operation of the parts thus far described is as follows:—

With the relay 15 deenergized as shown and at the instant that the resistance 10 is connected in shunt to the condenser 9, the system is in a non-oscillatory condition. As soon as the charge accumulated on the condenser 9 has leaked off through the resistance 10, which is only large enough to prevent sparking at the relay contacts 11, the polarizing potential impressed upon the grid of the device will be reduced to zero or some small value. The system will be restored to an oscillatory condition and at approximately the same instant space current will flow through the relay 15, the armature of which carries one of the contacts 11 will be pulled up, and the circuit including the resistance 10 will be opened whereby oscillating current will flow through the input circuit and will be rectified by the cooperative action of the cathode and grid to again begin charging the grid and the grid condenser.

The amplitude of the oscillating current flowing in the grid circuit being small and the condenser 9 of relatively large capacity, an appreciable but small interval is required to accumulate a charge of the desired value in the condenser. During this small interval the condenser gradually accumulates a charge which makes the grid negative relatively to its cathode.

Because of the gradually increasing charge supplied to the condenser 9, the potential impressed upon the grid 4 will continuously increase from zero, or some low value, to a relatively high negative value and the impedance of the tube will be continually increased and hence, the effective plate voltage and space current will be gradually decreased until some relatively low value is reached, at which the system ceases to oscillate.

As a consequence of the reduced space current flow, the relay 15, which is very fast acting and sensitive, fails to hold up its armature and the circuit of the resistance 10 is completed. The grid charge, therefore, is rather abruptly discharged through the relatively low resistance 10 and the system again begins to oscillate. This series of operations recurs cyclically.

With the arrangement described above, it will be seen that, during oscillating periods, the grid condenser is gradually charged to impose a continuously increasing back electromotive force to the flow of the direct current component of the grid current; the grid-cathode and plate-cathode impedances of the discharge device are gradually increased, and hence the effective impedance to the flow of oscillating and space currents

in the system is continuously increased from a minimum, at no grid potential, to a definite high value when the condenser has accumulated a definite charge. Thus, all three variables mentioned in Heising's paper, referred to above, are utilized to control the oscillatory condition of the system. Moreover, since the grid-cathode path is connected in parallel with the tuned frequency determining circuit of the system, the gradually increasing impedance of this path will cause the natural frequency of oscillation of the tuned circuit to vary and hence change the frequency of the oscillations generated.

It is pointed out that the shape of the oscillating wave is dependent mainly upon the frequency range and the rate at which the oscillations are repeated. The frequency in any instance is dependent upon the values of the inductance, capacity and effective resistance of the coils and condensers in the oscillating system, all of which are relatively constant, and the impedances of the coupled grid and plate circuits which are variable, since they are dependent upon the changing grid voltage. The rate at which the oscillations are repeated depends upon, among other things, the value of the capacity charged by the oscillating current flowing in the grid circuit and the quickness of response of the relay 15.

The constancy of operation of the oscillator is largely dependent upon the operation of the relay in the plate circuit. This relay should be very fast acting and sensitive and its operation can be considerably improved by providing it with an armature which does not chatter.

The coil 14 is inductively associated with a coil 17 included in the input circuit of a discharge device 18, which is shunted by a high resistance, to control its operation, whereby the amplified variable oscillating current generated by the oscillator is supplied through a repeating coil 19 to a load circuit.

As a practical use to which an oscillator of this type may be applied, it is herein shown as an element of an arrangement for testing telephone transmitters.

For this purpose the secondary winding of the repeating coil 19 is connected to a telephone receiver 20 which is supplied with oscillating current of variable frequency and amplitude within the audible range. The air waves produced by the vibration of the receiver diaphragm are projected through a tube 21 against the diaphragm of a microphone 22 to maintain it in a vibratory condition. By this means the granular material of the microphone is continuously agitated in a manner similar to that produced by speech waves.

The oscillator used in the microphone testing arrangement, includes an electric

discharge device having an external impedance of the order of 2000 ohms; when no polarizing potential is impressed upon its grid, and an amplifying factor of about 3.

5 Space current is supplied to the device at 110 volts, the input and output circuits are connected by a repeating coil, each winding of which has an impedance of one henry at 900 cycles, an ohmic resistance of about 10 42 ohms and the coefficient of coupling between the windings of the repeating coil is approximately 1. The condenser included in the input circuit has a capacity of two microfarads. The relay included in the 15 plate circuit has a resistance of 1000 ohms, is adapted to operate at three milliamperes and to release at 2.6 milliamperes.

Under these conditions the initial oscillating current flowing in the input circuit is 20 twelve milliamperes and the final input current is zero. The initial space current, average measured with a D. C. meter, is thirty milliamperes, and the final space current is 25 .4 millampere. The relay operates in approximately one two-hundredths of a second and is adapted to complete the leak path when the space current falls to .4 millampere. The damped wave is repeated about twenty-five times per second.

30 Fig. 2 illustrates an oscillogram of the oscillating current generated by the system described above. The frequency of the oscillating current at the point A on this curve is about 700 cycles and at the point B the 35 frequency is about 1900 cycles. The amplitude as shown by this curve varies simultaneously and inversely with the frequency. Assuming that at the point A the amplitude is represented by unity, the amplitude of the 40 wave at the mid-point C will be represented by one-half, and its amplitude at the point B by one-tenth.

The frequency range of the oscillating current produced by the oscillator described 45 above, corresponds to the most important portion of the range used in commercial telephony and the use of an oscillating current of variable frequency and amplitude which is interrupted, as supplied by this oscillator, serves to maintain the granular material of a telephone transmitter in an 50 agitated condition which is similar to that resulting from speech waves.

By using a discharge device having the 55 proper characteristics associated with input and output circuits having resistances, inductances and capacities of the proper values, an arrangement adapted to produce variable oscillating current above or below the audible frequency range may be provided.

While in the preceding description certain 60 circuits, specific details and a practical example have been above described for the purpose of completely and clearly disclos-

ing the nature and mode of application of the invention, it is to be understood that this invention is not limited to the specific circuits, details or use given, but only by the scope of the attached claims.

70

What is claimed is:

1. In a self-oscillating system including an electric discharge device having a leak path, the method of producing oscillations of variable frequency and amplitude which comprises alternately changing the conductivity of the leak path from a high to a low value, for varying the electrical conditions of the system.

75

2. The method of operating a three-electrode space discharge device which comprises causing the device to generate oscillations at a frequency within the audible range, and cyclically at a frequency adjacent the lower limit of the audible range 85 causing said device to react upon itself to stop and recommence oscillating.

80

3. A self-oscillating system comprising a three-electrode electric discharge device having coupled input and output circuits, means 90 for gradually varying the impedance of the space path of said device and abruptly restoring said space path to its original impedance.

90

4. A self-oscillating system comprising a three-electrode electric discharge device, and means for periodically causing the potential impressed upon one of the electrodes of said device to be varied and abruptly restored to its initial value whereby oscillations of variable frequency and amplitude are produced.

95

5. A self-oscillating system comprising an electric discharge device comprising a cathode, an anode, a control electrode and input 105 and output circuits therefor coupled in feed-back relation, means for impressing a gradually increasing potential upon said control electrode and for then abruptly discharging the impressed potential.

100

6. A self-oscillating system comprising an electric discharge device comprising a cathode, an anode, a control electrode and input 110 and output circuits therefor coupled in feed-back relation, means under the control of the generated oscillations to accumulate a gradually increasing potential upon said control electrode and for abruptly discharging the accumulated potential.

110

7. A self-oscillating system comprising an electric discharge device having a cathode, an anode, a control electrode, input and output circuits therefor coupled in feed-back relation, means for impressing gradually increasing potential on said control electrode, and means associated with the output circuit of the device for controlling the discharge of said potential.

115

8. A self-oscillating system comprising an electric discharge device having a cathode,

120

125

130

- an anode, a control electrode and input and output circuits therefor coupled in feed-back relation, means included in said input circuit for accumulating a gradually increasing negative potential charge and impressing said charge upon said control electrode, and means included in said output circuit for establishing a conductive path about said negative charge accumulating means.
10. 9. A self-oscillating system comprising an electric discharge device having a cathode, an anode, a control electrode and coupled input and output circuits therefor, a condenser included in the input circuit, a relay in the output circuit, a circuit in shunt of said condenser adapted to be controlled by said relay said condenser and said relay cooperating whereby a gradually increasing negative potential charge is impressed upon said control electrode and then discharged.
10. A generator of oscillations comprising a space discharge device provided with associated circuits and a relay included in one of said circuits, means for controlling said device to gradually reduce the current supplied to said relay until the latter operates to close another of said circuits, whereby said
- generator produces oscillations of continuously varying frequency.
11. A generator of oscillations comprising a space discharge device provided with external circuit connections and a relay, said circuit connections being provided with means including said relay for varying the impedance of a part of said circuit connections over a wide range, whereby said generator produces oscillations of continuously varying frequency.
12. A generating system for producing oscillations of frequency range and relative intensity of components adapted to simulate the energy distribution of the waves of audible speech which comprises a three-element space discharge device having coupled circuits associated therewith, and means included in said circuits for controlling said system to produce a succession of damped trains of waves, the components of each train increasing in frequency as their amplitudes decrease.
- In witness whereof, I hereunto subscribe my name this 27th day of November, A. D. 1923.

JOHN T. L. BROWN.
